UNITED STATES PATENT OFFICE.

DANIEL MAGNY, OF ISSOUDUN, FRANCE.

MACHINE FOR SETTING AND MIXING PIG BRISTLES.

Application filed May 2, 1922. Serial No. 558,032.

To all whom it may concern:

Be it known that I, DANIEL MAGNY, citizen of the French Republic, residing at Issoudun, Indre, in the Republic of France, have invented new and useful Improvements in Machines for Setting and Mixing Pig Bristles, of which the following is a specification.

This invention has for its object a machine for the preparation of pig bristles, and serving in particular for the setting and the mixing of the bristles. The "setting" consists, as is known, in disposing the bristles substantially parallel to each other and in such manner that their roots are all on the same side.

This machine comprises a "setting" drum of the general type described in applicant's French Patent No. 368009 of April 20th, 1906, as well as a device for receiving the "set" bristles, of a new construction.

The "setting" drum is formed by a fixed horizontal drum provided at the upper part with one or more apertures or feeding hoppers as well as with a chimney for the evacuation of dust, and whereof the cylindrical wall is formed at the bottom by a perforated sheet metal piece; in this fixed drum is caused to rotate a central shaft provided with two series in diametral opposition, of radial rods or teeth which in their rotation pass between the teeth of one or more stationary combs situated at the upper part of the drum, in such manner that the bristles placed in the drum are projected in the air by the ventilating effect of the rotating teeth, will be separated from each other upon encountering the upper fixed teeth, and will fall down by the action of gravity, which sets them upright and obliges them to pass through the perforated sheet metal piece with the root downward.

The receiving device comprises a set of passages slightly inclined with reference to the vertical, disposed below the perforated sheet metal piece and an endless belt which moves below these passages and upon which the bristles will lie down as they fall upon the same after having passed through the perforated sheet with the roots downward, the said belt extending outwardly of the passages in such manner as to afford an uncovered part wherefrom the operator may take the bristles in order to place them upright.

In the accompanying drawing which is given by way of example:

Fig. 1 is a side elevation of a machine for setting and mixing pig bristles constructed according to the invention, the setting drum being represented in section.

Fig. 2 is an end view, the drum being also seen in section.

The machine represented comprises a drum for setting the bristles constituted by a stationary cylindrical envelope or drum proper 1, disposed horizontally and supported by a frame or feet 1^a. This drum may for example have three metres length 70 and one metre diameter. It is provided throughout the whole length with two cleaning doors 2 and at the upper part with two feed hoppers 3 into which may be introduced the bristles to be set. A chimney 75 3^a which is necessary for the evacuation of dust is also provided at the upper part. An aspirator may be disposed at the end of the discharge pipe of this chimney in order to eliminate in a more complete manner 80 the dust and other impurities of the bristles. The lower part of the cylindrical wall of this drum is formed by a perforated sheet metal piece 4. The drum is divided, in the example represented, into three compartments by the vertical partitions 8, and the perforated sheet metal piece is made in three pieces each corresponding to a compartment.

In this stationary drum is caused to rotate a central shaft 5 provided with teeth 6 which form two series in diametral opposition. These teeth are constituted by metal rods whose ends move near the internal surface of the drum and particularly 95 of the lower perforated sheet metal piece. These rotating teeth also pass in their rotation between the teeth of two stationary combs 7 situated at the upper part of the drum, the teeth of these combs being also 100 formed preferably by metal rods. The shaft 5 carries at one end the actuating pulleys 10 and at the other end a pulley 11.

Below the drum 1 is mounted a device for receiving the bristles, composed of a series of passages 12 of sheet metal or other material, slightly inclined with reference to the vertical. These passages may have a rectangular or other section and may have for example about 30 centimeters height in 110 the part AB. They may be soldered or otherwise secured together to form one or

more groups which are attached below the drum through the intermediary of angle bars 13 and connecting members or bolts. The upper surface of the assemblage of passages 12 has a curved form in order to correspond to the shape of the perforated sheet metal piece 4. The lower surface of the assemblage of the passages is plane.

Below this lower surface is caused to move 10 an endless belt or apron 14 of india rubber or other material, carried at its ends by two rollers 15 and 16. The shaft of the roller 16 carries a gear wheel 17 in engagement with a worm 18 actuated by a pulley 19, 15 which is connected by a belt 20 with the pulley 11 carried by the shaft 5 of the drum. The apron 14 thus receives a continuous forward movement. The upper strand of this apron is supported by small rollers 25 mounted in supports 26. The shaft of the end roller 15 is carried by stretching bearings which may be displaced on the frame by means of screws 27 carrying the hand wheels 28. In this way the apron may be 20 perfectly stretched in order to form a table.

The machine is operated as follows:

The setting of the bristles is effected in the drum 1 in the following manner: The bristles introduced by small successive quantities into this drum are projected into the air by the teeth 6 or by the air current which they produce when rotating; they meet near the upper part of the drum with the teeth of the stationary combs 7, which separate 30 them and oblige them to fly about in the drum in such manner as to fall under the action of gravity, with the roots down, through the perforated sheet metal piece 4. The bristles which are thus set will descend in the 35 passages 12 and will fall upon the endless apron 14 upon which they will lie flat, with the root in front by reason of the forward 40 movement of this apron. By means of the latter, the bristles which are set and laid down will themselves come in front of the operator who is stationed at the end of the machine and removes the bristles as fast as they are presented in order to place them 45 upright. The dust remaining on the table falls into a receptacle and is thus automatically 50 removed.

As will be observed, this receiving device occupies but a very small space and is of a very simple construction and operation.

55 The drum 1 being divided into several compartments by the partitions 8 and the perforated sheet metal piece 4 being made in several pieces, the cleaning may be carried out rapidly and conveniently by removing and cleaning the perforated sheet metal piece of one of the compartments without interrupting the operation of the other two.

The machine described will permit a single female operator to prepare 100 kilogrammes of pig bristles per day; this amount

may also be increased by giving a greater size to the machine.

The invention is of course not limited to the details of construction represented and described, these having been chosen only by way of example.

Having now described my invention, what I claim as new and desire to secure by Letters Patent is:

1. A machine for "setting" and mixing pig bristles comprising a stationary horizontal cylindrical drum, the lower part of which is perforated, means for introducing pig bristles into said drum, a stationary comb on the inner surface of said drum, a central horizontal shaft rotatably mounted in said drum, means for rotating said shaft, radial arms on said shaft, a set of conduits arranged under the perforated lower part of said drum, said conduits being slightly inclined to the vertical, a straight endless apron mounted under said conduits and having its discharge end which extends beyond the set of conduits and means for supporting and actuating said endless apron. 90

2. A machine for "setting" and mixing pig bristles comprising a stationary horizontal cylindrical drum, the lower part of which is perforated, means for introducing pig bristles into said drum, a stationary comb on the inner surface of said drum, a central horizontal shaft rotatably mounted in said drum, means for rotating said shaft, radial arms on said shaft, a set of conduits arranged under the perforated lower part of said drum, said conduits being slightly inclined to the vertical, a straight endless apron mounted under said conduits and having its discharge end which extends beyond the set of conduits, means for supporting and actuating said endless apron and means for stretching the apron. 95

3. A machine for "setting" and mixing pig bristles comprising a stationary horizontal cylindrical drum, transverse partitions for dividing said drum into a plurality of compartments, perforated arcuated plates forming the lower walls of said compartments, respectively, means for introducing pig bristles into said drum, a stationary comb on the inner surface of said drum, a central horizontal shaft rotatably mounted in said drum, means for rotating said shaft, radial arms on said shaft, a set of conduits arranged under the perforated lower part of said drum, said conduits being slightly inclined to the vertical, a straight endless apron mounted under said conduits and having its discharge end which extends beyond the set of conduits and means for supporting and actuating said endless apron. 110

In testimony whereof I have signed my name to this specification.

DANIEL MAGNY.
